METAL CONTAINER

Alfred L. Kronquest, Syracuse, N. Y., assignor to
Continental Can Company, Inc., New York,
N. Y., a corporation of New York

Application February 18, 1932. Serial No. 593,915

1 Claim. (Cl. 220—54)

The invention relates to new and useful improvements in metal containers which are made easy to open by a tearing strip and which have an inserted collar in the region of the tearing strip. In containers of this type as now constructed the collar is made a permanent part of the can body by shaping the metal of the container collar after the parts are assembled, by welding, by soldering and by the friction grip of an oversize collar end forced into the container body.

An object of the present invention is to provide a container of the above type wherein the collar may be easily inserted in the container body either before or after it is flanged and held therein by the frictional grip of a portion of the collar with the container body.

A further object of the invention is to provide a container of the above type wherein the collar is spaced from the inner wall of the container to permit an outside slip connection with the end portion released by the removal of the tearing strip and wherein said collar is firmly attached to the container body by an outwardly projecting portion of the collar having frictional gripping contact with the inner wall of the container body.

A still further object of the invention is to provide a container of the above type wherein the container body is provided with an inwardly projecting portion having sealing gripping contact with the lower edge portion of the collar.

These and other objects will in part be obvious and will in part be hereinafter fully disclosed.

35 In the drawing which shows by way of illustration one embodiment of the invention:

Figure 1 is a vertical section through the upper portion of the container embodying the improvements.

40 Figure 2 is a vertical section on an enlarged scale through the upper portion and at one side of the container.

Figure 3 is a view partly in plan and partly in section of a portion of a collar to be inserted in 45 the container.

Figure 4 is a view similar to Figure 3, but showing the collar provided with an outwardly extending portion dimensioned to contact with the inner wall of the container.

50 Figure 5 is a view of the collar partly inserted in the flanged body of the container.

Figure 6 is a similar view but showing the collar partly inserted in the body of the container before it is flanged.

55 Figure 7 is a view in vertical section showing the collar fully seated in the container and the container flanged for receiving the end closure which is to be joined thereto.

The invention has to do with a container which 60 is made easy to open by a tearing strip formed

by scoring the metal of the body adjacent one end of the container. Within the container is a collar which is located in the region of the tearing strip, which collar is a permanent part of the container body left after the tearing strip is removed and serves to cover the lower raw edge of metal formed by the removal of the tearing strip.

The invention has particularly to do with the construction of the collar and the manner of permanently securing said collar with the container body. The collar is of considerably less diameter than the container body so that it may be easily inserted therein. The collar may be formed by drawing the metal of a blank so as to produce a seamless collar, or it may be formed from a strip the ends of which joined to form a cylindrical collar. At the upper edge the collar is rolled into a bead for concealing the raw edge of the metal and for strengthening and rounding up the collar.

Intermediate the upper and lower edges of the collar a bead is formed in the collar preferably by the use of dies so as to provide an outwardly projecting portion of a uniform diameter which is to contact with the body of the can for holding the collar in place. This collar is inserted in the can body either before or after it is flanged, and the outwardly projecting portion of the collar is so dimensioned that it will make a very tight friction grip with the inner face of the body of the container. The body wall of the container is also preferably provided with a bead which projects inwardly and which is so disposed that the lower edge portion of the collar contacting therewith will not only be gripped, but will have a tight sealing engagement with the wall of the container body, preventing the material within the container from passing into the space between the collar and the container body.

Referring more in detail to the drawing, the container body which is indicated at 1 is of the usual construction. It is preferably cylindrical in shape and provided with a side seam indicated at 2, which may be a lap seam or a lock and lap seam, but preferably a seam in the region of the collar is a lap seam. The can body is provided with an inwardly projecting bead 3 which is either rolled in the body wall or die-formed therein prior to the inserting of the collar in the can body.

The collar 4 as shown in Fig. 3 is cylindrical in shape and is rolled at the upper edge thereof as indicated at 5 for the purpose of concealing the upper raw edge of the collar and for strengthening and rounding up the collar. The collar may be made by drawing the metal from a blank so as to provide a seamless collar, or it may be made from a strip with the ends lapped and connected by a solder bond, or otherwise joined. The collar

as it is formed, as shown in Fig. 3 is then subjected to a machine for forming an outwardly projecting bead 6, intermediate the upper and lower edges of the collar. This bead is preferably formed by dies so that the extreme outer portion thereof will be of uniform diameter throughout and so dimensioned relative to the inner diameter of the container body as to have a tight frictional gripping contact therewith. The portion 7 of the collar beneath the bead 6 is, of course, of the same outside diameter as the portion 8 of the collar above the bead. The collar may be inserted in the can body after it is flanged, as indicated in Fig. 5, where the flange is shown at 9, or it may be inserted in the can body before it is flanged, as shown in Fig. 6. The lower edge portion of the collar is of considerably smaller diameter than the inner diameter of the container. Furthermore, the collar after it is provided with the bead 6 is not only symmetrical relative to the center of the collar, but will be maintained in this rounded condition so that it is only necessary to align the collar with the container body which has been rounded up and the portion 7 of the collar may be readily slipped into the mouth of the container. As noted, this can be accomplished whether the container has been flanged or has not been flanged. In either case it is only necessary to apply pressure against the outer curled edge portion 5 of the collar for forcing the collar into the container.

The bead 6 is dimensioned so that it is slightly oversize or larger in its extreme outer diameter than the inner diameter of the container. The rounded face of the lower side of the bead will expand the container or the metal of the bead will yield to permit the collar to enter the container and have a very firm frictional grip on the container throughout the region of the bead 6. This is a line gripping contact which may be made much firmer, yielding to any irregularities in the surface of the metal than can be accomplished by an extended frictional contact lengthwise of the container. Furthermore, the bead will grip the container uniformly throughout the entire circumference of the bead. When the can body is flanged before the collar is inserted, the collar is forced into the container body until the extreme outer portion of the curled edge 5 is slightly below the flange 9 as indicated in Fig. 7 of the drawing.

When the container body, as shown in Fig. 6, is not flanged, the collar is forced into the container body by the flanging die which simultaneously rolls the edge portion of the container body into a flange and seats the collar in a predetermined relation to the flange. This method of seating the collar and flanging the container body at the same time, forms the subject matter of a co-pending application, Serial No. 593,916, filed of even date herewith.

In either case when the collar is fully seated in the can body the lower edge 10 of the collar engages the bead 3 on the container body which is so dimensioned as to bring about a very tight frictional grip between the bead and this lower edge portion of the collar. Thus it is that the bead 3 with its frictional grip on the collar aids in the permanent attachment of the collar to the container body. Furthermore, the lower edge 10 of the collar terminates substantially at the crown of the inwardly projecting bead 3. This seals the connection between the collar and the container body so that the material will pass

through the collar in the emptying of the container and will not pass back of the collar and be discharged over the raw edge of the metal at the lower score line. The bead on the collar 6 also has a line sealing contact with the container body which will prevent discharge of the material over the edge of the lower score line if the material should pass the seal at the bead 3. There is, therefore, a double seal preventing the material even in liquid form from passing between the collar and the wall of the container body and insuring that all of the contents will be discharged through the collar.

By making the collar smaller than the container body a space is provided between the portion 8 of the collar and the body wall for an outside slip reclosure. In the present embodiment of the invention the end 11 is provided with a depending collar 12. This is formed by drawing the metal of the end so as to produce from the end a folded back portion of metal, producing a collar with a smooth lower edge. The end 11 is secured to the body as shown in the drawing by a double seam 13. It will be understood, however, that any form of hermetic seam may be used for joining the end to the body. It will also be understood that the outside slip reclosure may be made by placing the upper score line, which is indicated at 14, at a farther distance below the double seam, thus leaving a depending collar 105 formed from the body wall of the container. In this case the end 11 would not have the integral depending collar 12. The lower score line is indicated at 15 and is above the crown of the bead 6 of the collar so that when the tearing 110 strip is removed, the gripping contact of the collar with the container body is not disturbed.

It is obvious that minor changes in the shaping of the parts and in the details of construction may be made without departing from the spirit 115 of the invention as set forth in the appended claim.

Having thus fully described the invention, what I claim as new and desire to secure by Letters Patent is:

An easy opening container comprising a body having ends secured thereto, said body having spaced score lines at one end thereof forming a tearing strip for releasing the container end from said body, a collar located within said body, said collar at its upper and lower ends being of substantially uniform diameter and of smaller diameter than the container body, so that when said collar is inserted in said container, the upper portion thereof will be spaced away from the body of the container, said collar having an outwardly projecting portion intermediate the upper and lower edges thereof dimensioned and positioned so as to have a gripping sealing contact with the wall of the container adjacent and below the lower score line, said container body having an inwardly projecting portion below said lower score line contacting with the extreme lower edge of the collar, said collar at the upper end thereof being rolled inwardly to form a strengthening bead, said container end having means lying between a tearing strip and the upper portion of the collar and contacting with the body wall of the container and the outer wall of the collar for aiding in the removing of the tearing strip and also serving as an outside slip reclosure for the container when the tearing strip is removed.
